ELECTRIC SWITCH

Henry V. Nye, West Allis, Wis., assignor to Allis-Chalmers Manufacturing Company, Milwaukee, Wis., a corporation of Delaware

Application June 11, 1948, Serial No. 32,455

7 Claims. (Cl. 200—144)

1

This invention relates in general to electric switches or circuit breakers, and to the control of arcs formed by the opening of arcing contacts. The principal objects of the invention are the provision of new and improved electric switches or circuit breakers and new and improved arc control means.

One way to control an arc formed by the opening of an electric switch is to have two stationary arc runners for directing the arc into an arc extinguishing chute. The circuit is broken by a movable arm that draws an arc from one arc runner and transfers it to the other arc runner. With this arrangement however, the arc hangs on to the movable member too long and excessive heating and melting of the member may occur. Another way to control an arc is by means of a movable arc runner that makes contact with another arc runner, the movable arc runner being swingable about a fixed pivot. But the space requirements of an arc runner swingable about a fixed pivot make it difficult to reduce the overall size of the switch. Accordingly, another object of the invention is to provide an arc runner that will overcome the aforementioned difficulties.

Another object of the invention is the provision of new and improved arc drawing and extinguishing means, comprising arc runners in which the arc is free to move upwardly on the arc runners as soon as the arc is initially drawn, and in which the space requirements are minimized.

Another object of the invention is to provide a construction and arrangement in which the movable arc runner will travel toward the discharge end of the arc extinguishing chute, as the arc is drawn.

Another object of the invention is to provide a construction and arrangement of the movable arc runner so the entire length of the arc is led into the chute by the motion of the movable arc runner.

Another object is the provision of new and improved contact means.

Other objects will appear hereinafter as the description of the invention proceeds.

The novel features of the invention and how the objects are attained will appear from this specification and the accompanying drawing showing one embodiment of the invention and forming a part of this application, and all of these novel features are intended to be pointed out in the claims.

In the drawing:

Fig. 1 is a side elevational view of a switch or

2

circuit breaker embodying the invention, certain enclosing walls having been removed to better show the arrangement of parts within;

Fig. 2 is an enlarged partial section taken on line II—II of Fig. 1;

Fig. 3 is an enlarged partial section taken on line III—III of Fig. 1;

Fig. 4 is an enlarged partial section taken on line IV—IV of Fig. 1; and

Fig. 5 is an enlarged partial section taken on line V—V of Fig. 1.

Referring to Fig. 1, the switch here shown comprises arc drawing means, as will appear, and an arc chute 1, for receiving the arc, comprising any suitable walls of insulating material which may provide an enclosure open at the top and bottom. The chute may have suitably supported therein a series of spaced arc dividers 2 of any suitable material, as will be understood by those skilled in the art.

The arc drawing means comprises a stationary arcing contact member 3 and a composite movable contact member 4. The stationary arcing member 3 comprises an upwardly and outwardly extending arc runner 5 integrally formed with a stationary arcing contact portion 6, the stationary contact member 3 having a laterally extending base portion 7 that is supported by and attached to an end wall 8 of the arc chute 1. The upper end of the arc runner 5 is here shown as disposed between the wall 8 and the left hand end of the series of arc dividers 2. The base portion 7 is here shown as electrically connected, in series, with an arc blowout coil 9 to an electrical terminal 10. The electrical terminal 10 is in turn connected to a stationary main contact 11. The stationary main contact 11 supports and cooperates with a stationary auxiliary contact means 12 here shown as comprising two contacts 12a, 12b as shown in Fig. 2. The main contact 11, or that contact together with contacts 12a, 12b may be considered the principal stationary contact means. The contacts 12a, 12b are here shown as each provided with a projection 40 engaging the main contact 11 at opposite sides thereof. The contacts 12a, 12b are biased toward the stationary main contact 11 by springs 13 held by screws 14. The auxiliary contacts 12a, 12b can therefore spread as a conducting main switch arm 15 here shown as comprising two parallel spaced members 15a, 15b, forming part of the composite movable contact member 4, and here shown as swingable about a pivot 17, passes between and in engagement with the contacts 12a, 12b, to engage opposite sides of the main sta-

tionary contact 11. The pivot 17 may also serve as an electrical terminal for current flow to the switch arm 15. Movement of the contacts 12a, 12b toward the main contact 11 is limited by suitable stops 41.

The members 15a, 15b are movable relatively to each other in the direction of the axis of a bolt 23, seen in Figs. 1 and 4, to an extent limited by the bolt 23, a nut 23a thereon, a spring 24 and a spring retainer 25, as shown in Fig. 4. The members 15a, 15b are thereby able to spread sufficiently to pass over and in engagement with the main contact 11 and yet pass between the auxiliary contacts 12a, 12b, as shown in Fig. 2.

It will be noted from the foregoing description that there are, as shown in Fig. 1, three contacts adapted to be engaged by the main movable switch arm 15, namely, the stationary main contact 11, the stationary auxiliary contacts 12a, 12b and the stationary arcing contact portion 6.

The composite movable contact member 4 comprises besides the main switch members 15a, 15b, a floating arc runner 16. The arc runner 16 is of composite construction as here shown and is connected at one end to the members 15a, 15b by a composite pivot 18a, 18b, as will more fully appear. The other end 19 of the runner 16 is slidably connected in a slot 20 of a guiding means 21 by a pin 22, as will more fully appear and as shown in Fig. 1 and Fig. 5. The guiding means 21 may be supported in any suitable way by the right hand end wall 8a of the arc chute 1.

The floating arc runner is here shown as comprising two parallel, spaced members 16a, 16b as best seen in Fig. 3 and Fig. 5. The two members 16a, 16b are desirably integrally jointed by a base member 26, thereby forming an integral inverted U-shaped channel member.

The base member 26 terminates at one end 45 so as to leave the right hand ends of the members 16a, 16b free, forming arms at opposite sides of the guiding means 21. As shown in Fig. 5, the pin 22 extends through both members 16a, 16b. Spacing collars 46, 47 may be provided between the respective inside surfaces of the members 16a, 16b and the respectively adjacent sides of the guiding means 21. The pin 22 may be held in position by cotter pins 48 through the pin 22, or in any other suitable way.

The base member 26 terminates at the other end 49, short of the inner surface of the stationary arc runner 5, as seen in Fig. 1. This leaves the left hand ends of the members 16a, 16b free, forming arms at opposite sides of the members 15a, 15b. Since the movable arc runner comprises two members 16a, 16b and the movable main contact arm to which it is pivoted comprises two parallel members 15a, 15b, two pivot pins 18a, 18b are provided (see Fig. 3) the pivot pin 18a connecting the members 15a and 16a and the pivot pin 18b connecting the members 15b and 16b. As here shown the pins 18a and 18b have heads 50 which are disposed in respective recesses in the opposed inner faces of the members 15a, 15b, so as to leave those inner faces free and unobstructed for engagement with the opposite faces of the contact 6. The pins 18a, 18b may be held in position by cotter pins as indicated.

The blowout coil 9 is disposed about a generally U-shaped magnetic core having a bight 27 and having legs extending alongside the respective side walls of the chute 1. One of the legs, 60, of the core 27 is indicated in Fig. 1. The blowout coil 9 provides a magnetic field across the

arc chute 1 for promoting upward movement of the arc (as viewed in Fig. 1) that is, movement toward the discharge end of the arc chute 1.

It will be evident that while making the arc runner 16 and the main contact 15 of double arm form has advantages, this construction is not essential. As far as the electrical functions of the switch are concerned, and particularly the operation of the arcing contact means thereof, single arm parts may be utilized.

The operation of the switch illustrated is as follows: When the switch is in the closed position as shown in Fig. 1, the principal path for electric current, the path of least resistance, may be traced from the fixed pivot 17 to the movable main contact member 15 to the stationary main contact 11, to the electrical terminal 10. If the current path is to be interrupted, the movable contact member 15 is caused to swing clockwise about the pivot 17 by any suitable means. This movement initially causes disengagement of the movable contact member 15 from the stationary main contact 11, without substantial arcing, leaving a current path through the movable contact member 15 and the stationary auxiliary contact 12. Further movement of the movable contact member 15 causes disengagement thereof from the auxiliary contact 12 thereby causing current to flow through the blowout coil 9 in series with the arcing contact 6 and the upper end of the movable contact member 15, which latter two contacts have not, as yet, separated. Still further movement of the movable contact member 15 causes disengagement of the latter from the arcing contact 6. An arc is thereby drawn, in a substantially horizontal direction, between the stationary arcing contact 6 and at least one of the members 15a, 15b, in the double arm construction illustrated. At the point of initial arcing, the members 15a, 15b may be provided with contact inserts 28 and 29 (see Fig. 1 and Fig. 3). The inserts 28 and 29 may be made of a metal having more desirable contact properties than those of the members 15a, 15b. The arc will rise with one end on the stationary arc runner 5 and the other end momentarily on at least one of the members 15a, 15b from which it is quickly transferred to the floating arc runner 16, and, more particularly, to top 26 thereof. It will be understood by those skilled in the art that the arc rises due to the field set up by the arc itself which will be assisted by the blowout coil 9 if employed.

As the switch is opened the floating arc runner 16 will move relatively to the movable contact member 15, rotating counter-clockwise about the floating pivots 18a, 18b, because the other end 19 of the movable arc runner 16 slides up the slot 20 of the guiding member 21. This causes decrease of the angle A between stationary arc runner 5 and the floating arc runner 16. Also, the end 19 of the floating arc runner 16 is led deeper into the arc chute 1 (toward the discharge end of the chute) as the arc moves upwardly. The entire length of the arc is therefore led into the chute 1 and extinguished.

It will be evident that as soon as contact is broken between the movable contact member 15 and the stationary contact 6, the so established arc will not hang on the upper end of the contact member 15 but will quickly transfer to the floating arc runner 16 and move upwardly along the runner 16 as the runner is swung about the floating pivots 18a, 18b. Thus all the advantages of an arc runner swingable about a fixed

pivot are retained while at the same time obviating its disadvantages.

It will also be apparent that broadly, as far as the operation of the arcing contact means, comprising the arc runners 5 and 16, is concerned it is not material whether the floating arc runner 16 is carried by a swingably mounted member such as movable contact member 15, or whether separating movement of the arc runners is obtained by any other suitable means, and/or the initial establishment of the arc takes place directly between portions of the contact 6 and floating arc runner. Furthermore, the illustrated guiding means for causing a decrease in the angle formed between the arc runners 5, 16 as the runners are separated to draw an arc, while specifically advantageous, may be replaced by any other suitable means for accomplishing that result as will readily occur to those skilled in the art.

From the foregoing it will be apparent to those skilled in the art that the illustrated embodiment of the invention provides a new and improved arcing contact means, arc control means, and electric switch, and accordingly accomplishes the objects of the invention. On the other hand it will also be obvious to those skilled in the art that the illustrated embodiment of the invention may be variously changed or modified, or features thereof, singly or collectively, embodied in other combinations than that illustrated, without departing from the spirit of the invention or sacrificing all of the advantages thereof, and that accordingly the disclosure herein is illustrative only, and the invention is not limited thereto.

It is claimed and desired to secure by Letters Patent:

1. Arcing contact means, comprising: first and second conducting members cooperable to draw an arc between them upon separation thereof; an arc chute for receiving the arc drawn between said members, said chute having a discharge end; means for causing separation of said first and second conducting members, comprising a movable portion and a connection between one of said members and said movable portion whereby said one of said members is swingable with respect to said portion; and guiding means responsive to said separating movement for causing said one of said members to swing with respect to said portion and to actuate said member toward the discharge end of said chute, said guiding means comprising a relatively stationary part with respect to which said one of said members is slidable.

2. Arcing contact means, comprising: first and second conducting members cooperable to draw an arc between them upon separation thereof; one of said members comprising an elongated channel of U-shaped cross section having a base forming an arc runner, a movable element disposed between arms at one end of said channel, and a connection between said element and said arms whereby said channel is swingable with respect to said elements; means for causing separation of said first and second conducting members; and guiding means responsive to said separating movement for causing said channel to swing with respect to said element, said guiding means having a part disposed between arms at the other end of said channel.

3. Arcing contact means, comprising: first and second conducting members cooperable to draw an arc between them upon separation thereof; one of said members comprising an elongated

channel of U-shaped cross section having a base forming an arc runner, a movable element disposed between arms at one end of said channel, and a connection between said element and said arms whereby said channel is swingable with respect to said element; means for causing separation of said first and second conducting members; and guiding means responsive to said separating movement for causing said channel to swing with respect to said element, said guiding means having a slotted part disposed between arms at the other end of said channel, and a pin carried by said last named arms and disposed through said slot.

4. An electrical switch, comprising: a stationary arcing contact; a movable arcing contact cooperating with said stationary arcing contact to draw an arc therebetween upon separation thereof, said movable arcing contact comprising a first pair of parallel spaced conducting members mounted for cooperation with said stationary arcing contact and a second pair of parallel spaced conducting members pivotally mounted on the contact engaging end of said first pair of conducting members for swinging movement therewith; and stationary principal contact means engageable by said first pair of conducting members.

5. A switching device, comprising: a stationary arcing contact; a movable arcing contact cooperating with said stationary arcing contact to draw an arc therebetween upon separation thereof, said movable arcing contact comprising a first pair of parallel spaced conducting members mounted for cooperation with said stationary arcing contact and a second pair of parallel spaced conducting members pivotally mounted on the contact engaging end of said first pair of conducting members for swinging movement therewith; an arc chute for receiving the arc upon separation of said arcing contacts at one end thereof and for discharging the arcing products at the other end; and guiding means responsive to separation of said arcing contacts for causing said second pair of conducting members to swing toward the discharge end of said chute causing the arc to move toward the discharge end of said chute in response to arc drawing movement of said movable arcing contact.

6. A switching device, comprising: a stationary arcing contact; a movable arcing contact cooperating with said stationary arcing contact to draw an arc therebetween upon separation thereof, said movable arcing contact comprising a first pair of parallel spaced conducting members mounted for cooperation with said stationary arcing contact and a second pair of parallel spaced conducting members pivotally mounted on the contact engaging end of said first pair of conducting members for swinging movement therewith; an arc chute for receiving the arc upon separation of said arcing contacts at one end thereof and for discharging the arcing products at the other end; a stationary main contact engageable by the inside surfaces of said first pair of conducting members and comprising auxiliary contact fingers engageable with the outside surfaces of said first pair of conducting members; and guiding means responsive to separation of said arcing contacts for causing said second pair of conducting members to swing toward the discharge end of said chute causing the arc to move toward the discharge end of said chute in response to arc drawing movement of said movable arcing contact.

7. Arcing contact means, comprising: first and second conducting members cooperable to draw an arc between them upon separation thereof; an arc chute for receiving the arc drawn between said members, said chute having a discharge end; means for moving one of said members to cause separation of said first and second conducting members; an arc runner pivotally mounted on said one of said members, and guiding means for causing said arc runner to swing with respect to 10 said one of said members toward the discharge end of said chute responsive to said separating movement, said guiding means comprising a relatively stationary part with respect to which said arc runner is movable.
